UNITED STATES PATENT OFFICE.

GUSTAVE STICKLEY, OF SYRACUSE, NEW YORK.

DESIGN FOR A LIBRARY TABLE-DESK.

SPECIFICATION forming part of Design No. 35,044, dated September 3, 1901.

Application filed July 31, 1901. Serial No. 70,433. Term of patent 7 years.

To all whom it may concern:

Be it known that I, GUSTAVE STICKLEY, a citizen of the United States, residing at Syracuse, in the county of Onondaga, State of New York, have invented and produced a new and original Design for Library Table-Desks, of which the following is a specification, reference being had to the accompanying drawing, forming a part thereof, in which I show the same in an isometrical view.

As shown in the drawing, the leading or material feature of my design comprises a desk having a top *a*, supported by angular uprights *a'* in front and *b* at the rear, the uprights *a* engaging with the under face of the top and the rear upright *b* extending above the top, as shown.

b' is a cleat secured to the face of the upper portions of the uprights *b* above the top. Beneath the top and extending between the uprights *a'* and *b* are cross-bars *c*, the ends extending through the uprights *a'*, as shown at *c'*, and *d* shows vertically-arranged panels extending between the top *a* and cross-bar *c*.

e is a cross-bar extending between the upright *a'* and beneath the top, and *e'* shows drawers.

Between the legs *a'* and *b* are cross-bars *f*, having their ends extending clear through, as shown at *f'*, and *g* is a shelf having a portion of its front edge cut away, as shown at *g'*, and its ends extending through the cross-bar *f*, as shown at *h*, and *o* shows dowel-pins extending through the ends *h*, the whole forming a unique library table-desk as an article of manufacture.

Having thus described my invention, what I claim, and desire to secure by Letters Patent, is—

The design for a library table-desk as herein described and shown.

In witness whereof I have hereunto set my hand this 26th day of July, 1901.

GUSTAVE STICKLEY.
